UNITED STATES PATENT OFFICE.

MARION L. THOMAS, OF PASADENA, CALIFORNIA.

SMOKING IMPLEMENT.

1,118,828.

Specification of Letters Patent. Patented Nov. 24, 1914.

Application filed December 16, 1913. Serial No. 807,127.

To all whom it may concern:

Be it known that I, MARION L. THOMAS, a citizen of the United States, residing at Pasadena, in the county of Los Angeles and 5 State of California, have invented new and useful Improvements in Smoking Implements, of which the following is a specification.

The invention relates to tobacco, and has 10 for an object to provide a smoking implement for use in consuming tobacco.

The invention embodies, among other features, the provision of a device which can be used for smoking cigars, cigarettes or in the 15 nature of a pipe and which provides a structure whereby the user can indulge in a comfortable smoke without having to bother with flicking ashes off of the cigar, cigarette or the pipe portion of the device and where- 20 in, furthermore, smoke will be prevented from escaping from the body of the device and can only be drawn through the usual mouthpiece.

The invention still further contemplates a 25 device which can be carried in the pocket while in use and wherein only the mouthpiece and the tube communicating with the device and forming a part thereof will be visible.

30 In the further disclosure of the invention reference is to be had to the accompanying drawings, constituting a part of this specification, in which similar characters of reference denote corresponding parts in all the 35 views, and in which:

Figure 1 is a side elevation, showing the cover applied, with the cover, parts of the body of the device and a portion of the mouthpiece broken away, with the under- 40 lying parts shown in section; Fig. 2 is a perspective view of a cigarette holding member which can be used in connection with the device; and Fig. 3 is a perspective view of a tobacco holder adapted to contain loose tobacco and which can be used in connection 45 with the device.

Referring more particularly to the views, I provide a substantially frusto-conical body 10 having a central passage 11 terminating 50 at its upper end in a basin 12, the portion of the body 10 forming the wall of the basin 12 being preferably threaded to receive a cover 13 with the other or tapered end of the body

10 being carried by a hook-like stem 14 having connected thereto a suitable flexible tube 55 15 carrying a mouthpiece 16.

As stated, the device is adapted for use in smoking cigarettes, cigars or loose tobacco and in the event that it is desired to smoke a cigar there is provided a cigar holding 60 member 17 consisting of a body 18 adapted to receive one end of the cigar and a tapered stem 19 carried by the body 18 and having a passage communicating therewith. The tapered end of the stem 19 is adapted to fit 65 into the upper end of the passage 11 as shown, and, as mentioned, the cigar is held in the cigar holding member 17 so that the cigar will lie in a substantially vertical position. The cigar is now ignited and the 70 cover 13 is then placed upon the body 10, the said cover being preferably threadedly engaged with the body. The upper end of the cover 13 is closed and preferably provided with a central opening 20 which is 75 normally closed by a spring-engaged disk-like valve 21, the spring provided for holding the valve in position to close the opening 20 being one which, when the user sucks upon the mouthpiece 16, will permit the 80 valve 21 to be moved away from the under side of the top of the cover 13, thus partially uncovering the opening 20 so as to permit air to enter the cover, it being readily understood that it is necessary to have a 85 certain amount of air in the cover in order that the cigar or other smokable substance will burn properly and, furthermore, in order that the user can create sufficient suction to receive the desired smoke in his mouth. 90

When it is desired to smoke a cigarette with the device there is provided a cigarette holding member 22 and which consists of a body 23 smaller than the body 18 and adapted to hold a cigarette of the usual construction, the said body having a tubular stem 24 of a tapered nature and which extends into the upper end of the passage 11 when the cigarette holding member 22 is applied to the body 10 in the same manner as the cigar 100 holding member 17 is applied to the body. Similarly, when it is desired to smoke loose tobacco use is made of a tobacco holding member 25 consisting of a bowl-like body 26 having a tapered stem 27, with the tapered 105 stem 27 adapted to fit into the upper end

of the passage 11 and the bowl-like body 26 made sufficiently large to accommodate an ordinary pipe bowl full of tobacco but restricted in cross section so that the cover 13 can readily be applied to the body 10 without interfering with the tobacco holding member 25.

From the foregoing description it will be seen that in the use of a device of the character described the smoker will not have to bother with any ashes produced while the substance which is being smoked is consumed and the basin 12 is provided to receive any ashes which may fall from a cigar or cigarette when the same is used in connection with the respective cigar and cigarette holding members described herein as applied to the body 18.

When the cigar, cigarette or loose tobacco to be smoked has been placed in the respective members provided therefor and the said member engaged with the body 18 and ignited, the cover 13 is applied to the body as mentioned heretofore and the body and cover can then be conveniently placed in the pocket so that the user will not have to hold the same in his hand and need only retain the mouthpiece in his mouth. Thus there is provided a device whereby a person can comfortably smoke without having the smoke enter his eyes, while at the same time he can use both hands and the smoking implement provided herein will not interfere with the use of his hands for other purposes.

Having thus described my invention, I 35 claim:

In a smoking implement, the combination with a substantially frusto-conical body having a central passage terminating at its upper end in a basin and communicating with the interior of the body, of a threaded wall forming the said basin and constituting the upper end of the body, a tobacco holding member provided with a longitudinal passage and adapted to have its lower end removably fitted into the passage in the body whereby the said member will communicate with the interior of the body and will extend through the basin in the body, a cover for threaded connection with the outer 45 threaded wall of the body to inclose a smokable article held on the tobacco holding member, and a spring-actuated valve normally closing an aperture in the cover and lying wholly within the cover and on the 50 under side of the top thereof, said valve being adapted to be operated to uncover the aperture, by suction created in the body and the passage and communicating with the interior of the cover through the smokable article supported in the tobacco holding member.

In testimony whereof I affix my signature in presence of two witnesses.

MARION L. THOMAS.
